[57] CLAIM

The ornamental design for a combined tethered golf
tees and base therefor, as shown and described.

DESCRIPTION

FIG. 1 is a perspective view of a combined tethered golf
tees and base therefor showing my new design;

FIG. 2 is a top plan view thereof;

FIG. 3 is a bottom view thereof;

FIG. 4 is a side elevational view thereof;

FIG. 5 is a side elevational view of the side opposite
that shown in FIG. 4;

FIG. 6 is a front elevational view thereof; and,

FIG. 7 is a rear elevational view thereof.

The broken lines indicate indeterminate length of the
tether.
